CLAIM

The ornamental design for a redundant heat sink module, as shown and described.

DESCRIPTION

FIG. 1 is top front perspective view of a redundant heat sink module;

FIG. 2 is a bottom front perspective view of the redundant heat sink module of FIG. 1;

FIG. 3 is top rear perspective view of the redundant heat sink module of FIG. 1;

FIG. 4 is a bottom rear perspective view of the redundant heat sink module of FIG. 1;

FIG. 5 is a top view of the redundant heat sink module of FIG. 1;

FIG. 6 is a bottom view of the redundant heat sink module of FIG. 1;

FIG. 7 is a front view of the redundant heat sink module of FIG. 1;

FIG. 8 is a rear view of the redundant heat sink module of FIG. 1;

FIG. 9 is a left side view of the redundant heat sink module of FIG. 1; and,

FIG. 10 is a right side view of the redundant heat sink module of FIG. 1.

The broken lines shown in the drawings illustrate portions of the heat sink module and form no part of the claimed design.
